UNITED STATES PATENT OFFICE

2,144,504

TOP MOUNTING STRUCTURE FOR REFRIGERATOR CABINETS

Roland H. Money, Cincinnati, Ohio, assignor to
 The Crosley Corporation, Cincinnati, Ohio, a
 corporation of Ohio

Application December 31, 1934, Serial No. 759,941

6 Claims. (Cl. 220—9)

Most refrigerator cabinets have a metal outer shell and a metal top member which fits on the upper edges of the metal shelving. Some refrigerators of course contain only the refrigerated compartment, the high pressure side of the mechanical refrigeration unit being located elsewhere. Other refrigerators have a machine compartment located below the refrigerated compartment, and still other refrigerators have the machine compartment located above the refrigerated compartment. I shall describe my invention in connection with a cabinet of the last class, it being understood that my invention is not restricted thereto. In cabinets of the type where there is a machine compartment above the refrigerated compartment, and especially where the motor, compressor and condenser are located above a base to be placed in such compartment, while the evaporator is suspended from the base so as to extend into the refrigerated compartment, and where the entire mechanism is removable as a unit from the cabinet, the necessity for a removable top member will be clearly apparent. Since the top member and the cabinet are usually of metal, it has been the practice in the past to place between the top and the upper edges of the cabinet a sealing or binding strip of rubber, or the like, especially for the purpose of preventing rattling upon vibration. The rubber beading or bushing is usually made in strips of generally T-shaped cross section, the flange or leg of the T being designed to go between the top and the upper edges of the cabinet and the cross bar of the T, usually of externally rounded configuration, overlies and covers the joint between the top and shell of the cabinet. Frequently such strips are made with a portion of the T leg bent over so as to engage a flange on the top of the cabinet. The use of such rubber strips has been found disadvantageous in certain respects. They are under some conditions liable to displacement, especially when the top is removed. Since they are not continuous all around the surface of the cabinet, there are unsightly joints and sometimes spaces between adjacent portions of the rubber strip.

The general objects of my invention are the provision of a structure in which these defects are eliminated, as well as the provision of a structure which, while providing a secure, resilient support for the top, is not liable to displacement of parts, permits the use of shorter sections of rubber or other resilient material, and furnishes a better and more attractive finish for the cabinet, as will hereinafter be more fully described.

These and other objects of my invention which will be apparent to one skilled in the art upon reading these specifications, I accomplish by that certain construction and arrangement of parts of which I shall describe an exemplary embodiment. Reference is now made to the drawing, wherein:

Figure 1 is a vertical sectional view of an exemplary cabinet embodying my invention.

Fig. 2 is a plan view thereof with the top removed.

Fig. 3 is an enlarged sectional view of my moulding and finishing structure.

Essentially in the practice of my invention, as I shall hereinafter set forth, I provide a metallic finishing member which is substantially the only thing ordinarily visible from the outside of the cabinet at the joint between the body and the top. This metallic finishing member is adapted to contain the resilient supporting devices which, because of the fact that they are hidden, not only may be cheaper in cost because less complicated, but also may be used in short sections so that wastage is eliminated. None of the joints between adjacent pieces of resilient material are visible from the outside, and indeed adjacent pieces may be spaced from one another without visual detriment, and with a saving of material, if this is desired.

I have shown in Fig. 1 a metallic cabinet having body walls 1. I have also indicated at 2 a refrigerated compartment in the cabinet, and at 3 a door. A compressor device 4 has been indicated in a machine compartment 5 above the refrigerated compartment. The details of these mechanisms do not form a limitation upon my invention, and will not be described.

I have indicated at 6 a top for my cabinet. The details of the top mounting will be more clearly appreciated from Figure 3, where I have shown a top wall 6 of the cabinet terminating in a bent over flange 7. The upper edge may be reinforced by a metallic angle piece 8 if desired. The top 6 is shown as having rounded upper edges, and terminating beneath in a bent over flange 9. It would be impracticable to cause the flange 9 to rest directly upon the flange 7 of the body, for the reason (1) that it would be liable to displacement, and (2) that it would be noisy on account of vibrations. I provide a mounting member of metal in the form of a beading adapted to follow the upper edges of the cabinet and to form a finishing member therefor. This metal mounting member is indicated at 10 in the figures, and it may be a continuous loop-shaped piece of

metal, or it may be joined as desired at the back of the cabinet. Again, it may be fastened, as will hereinafter be described, to the body of the cabinet. The metal member 10 may conveniently be formed in dies or by a rolling or bending operation, and then bent in dies to go around the corners of the cabinet, which in most modern constructions will be rounded. It would be possible, of course, to make this member as a single stamping, but this ordinarily is not economical. It comprises a flange member 11 adapted to overlie the body flange 7 and terminating beyond the body in a bent over portion 12. The metal is continued beyond this bent over portion in a reverse bend 13, interspaced therefrom, and adapted to form an attractive oval beading, the metal terminating at a point marked 14 so as to leave a space for the insertion into the device of suitable resilient mounting means. I have shown one form of such resilient mounting means in the figures as a rubber piece comprising a flange portion 15, and a head 16 on the flange extending upwardly therefrom. The flange 9 of the top of the cabinet rests upon the flange 15 of the resilient piece, while the head 16, which is substantially contained in the oval beading portion 13 of the metallic finishing member, serves to prevent lateral displacement of the top, and to prevent rattling if the top contacts it.

By reason of the use of continuous beading 13, the flange 11, which may be spot welded or otherwise fastened if desired, to the body flange 7 and reinforcement 8, I am able to use interpaced portions of the resilient mounting member as clearly shown in Figure 2. The joints between these members will not normally be visible from the outside of the cabinet, which to all intents and purposes will appear to be finished by a continuous metallic beading 10.

Modifications may be made in my invention without departing from the spirit thereof.

Having thus described my invention, what I claim as new and desire to secure by Letters Patent, is:—

1. In combination, a metallic refrigerator cabinet having inwardly turned upper flanges, a metallic top having inwardly turned lower flanges, separate resilient mounting means located in part at least between said flanges, a metallic beading covering and concealing the exposed portions of said mounting means, said metallic beading comprising a flange like portion adapted to lie between the flanges of said body and said top, and fastened to the flanges of said body, and a hollow portion extending beyond the juncture thereof.

2. In combination, a metallic refrigerator cabinet having inwardly turned upper flanges, a metallic top having inwardly turned lower flanges, separate resilient mounting means located in part at least between said flanges, a metallic beading covering and concealing the

exposed portions of said mounting means, said metallic beading comprising a flange like portion adapted to lie between the flanges of said body and said top and fastened thereto, and a hollow portion extending beyond the juncture thereof, said resilient means having a head adapted to extend into the hollow portion of said metallic beading.

3. In combination, a metallic refrigerator cabinet having inwardly turned upper flanges, a metallic top having inwardly turned lower flanges, separate resilient mounting means located in part at least between said flanges, a metallic beading covering and concealing the exposed portions of said mounting means, said metallic beading comprising a flange like portion adapted to lie between the flanges of said body and said top and fastened to said inwardly turned flanges, and a hollow portion extending beyond the juncture thereof, said resilient means having a head adapted to extend into the hollow portion of said metallic beading, said head having an inwardly disposed abutment to prevent lateral displacement of said top.

4. In combination, a metallic refrigerator cabinet having inwardly turned upper flanges, a metallic top having inwardly turned lower flanges, separate resilient mounting means located in part at least between said flanges, a metallic beading covering and concealing the exposed portions of said mounting means, said metallic beading comprising a flange like portion adapted to lie between the flanges of said body and said top, and a hollow portion extending beyond the juncture thereof, said flange of said beading being attached to said flange of said body.

5. In combination with a refrigerator cabinet, a finishing device comprising a metallic loop shaped member having a flange fastened to the tops of the walls of said cabinet, and a hollow portion extending downwardly, outwardly and upwardly therefrom forming a hollow beading, and separate resilient means lying in part at least within said beading, the top of said cabinet resting on said resilient means, said resilient means comprising a head portion forming an upwardly extending abutment and a flange portion overlying in part at least, the flange portion of said metallic member.

6. In combination with a refrigerator cabinet and a top therefor, a metallic finishing member having a flange lying between the juncture of said members and fastened to said cabinet, and a bead shaped portion lying therebeyond, said bead shaped portion being hollow, and separate resilient mounting means contained at least partially therein, said resilient means having a flange-like portion overlying at least in part said first mentioned flange.
